Spinning Mule.

N° 102,537.

Patented May 3, 1870.

United States Patent Office.

WILLIAM HACKLEY, OF MOOSUP, CONNECTICUT, ASSIGNOR TO HIMSELF
AND CHARLES T. ALMY, OF SAME PLACE.

Letters Patent No. 102,537, dated May 3, 1870; antedated April 25, 1870.

IMPROVEMENT IN SELF-ACTING MULE FOR SPINNING.

The Schedule referred to in these Letters Patent and making part of the same.

To all whom it may concern:

Be it known that I, WILLIAM HACKLEY, of Moosup, in the town of Plainfield, county of Windham, and State of Connecticut, have invented certain new and useful Improvements in the Mason Self-acting Spinning-Mule, so-called; and I do hereby declare the following to be a full, clear, and exact description of the same, reference being had to the accompanying drawings making a part thereof, in which—

Figure I represents a vertical, and

Figure II, a side view of the improvements, with so much of the mule and its arrangements as are necessary to show said improvements.

Figure III represents the shaft X, with the clutch-gear E² E³, the bent-bar E⁵, the ratchet E⁶, the pawl E⁷, the loose gear E⁸, and the spring E⁹.

Figure IV shows the fast rim-pulley G¹, containing the ratchet G³, and the pawls G⁸.

Figure V, the openings on the disk of the clutch E².

Figure VI, the catch-gear F¹ F³, the finger F⁴, the end of the lever J, and the friction-clutch F⁵ C² on the shaft F².

The same parts in the different figures are indicated by the same letters.

The invention relates to the backing-off and winding-on motions of the mule, and which are in operation from the time the driving-belt is transferred to the second driving-pulley A until it is carried back to the first, and includes, also, modes of regulating the starting of the mule-carriage in running in or out.

It consists in improving and simplifying the apparatus now employed, in part, by substituting new devices and, in part, by dispensing with the regulator and other arrangements heretofore considered essential in running said mule.

By dispensing with the machinery hereinafter mentioned, the amount of power required to run the mule, its liability to derangement and breaking down, and the expense of repairs as well as the loss in time and production, are lessened.

By my alterations the mule is improved in these respects, yiz: that while in the present Mason mule, the motions above mentioned are not always certain, and the apparatus sometimes gets out of order and breaks, under the plan hereinafter described the first are made exact and positive, and the machinery seldom fails, if ever, to operate accurately.

Whatever be the speed of the mule-carriage, the backing-off and winding-on motions always act and work in conformity and simultaneously with the follower and rack. The follower does not move until the yarn is in readiness to back off, nor will the rack run in until the yarn is in position to be wound on.

As a further advantage, the improved mule, when backing off or winding on, can be stopped at any position or point in the operation, and then be started up

from that point, to continue and finish the operation without breaking the yarn or deranging the machinery.

The backing off and winding on can, besides, be effected more rapidly, thereby enabling the mule to produce more yarn.

The improvements do not affect nor alter the apparatus or gearing connected with the movement of the carriage, except to bring the running-in motions into gear promptly, and to modify and graduate the motion of the carriage so as to prevent a violent and abrupt starting when commencing to run in or out; or, the apparatus now used to regulate the speed of the spindle to the size of the cop in winding on, or the position of the cop-rail for the same purpose, but are confined to the mode of operating the friction-band pulley E, its shaft and connections, with the usual upper rack D⁴, the cop-rail shaft N, the shaft F², usually known as the scroll-clutch shaft, and a friction-gear, S', on the shaft S.

In general terms these may be enumerated as follows, viz:

The band-pulley E and the band are stopped and the reverse motion effected by friction alone. When the friction is removed the pulley is simultaneously connected with the rack D⁴, so that they are operated alike by the same power and run in correspondence while the yarn is winding on.

As an exact and positive action is thus produced, and the backing off no longer obliges the friction-band pulley to move the rack D⁴ when its motion is reversed, as in the Mason mule, the apparatus on the rock or cop-rail shaft N for bringing back the rack and regulating said movement before the winding on commences, including also the chain so far as it is constructed to gear into the spur-gear, is dispensed with as no longer necessary.

The rock or cop-rail shaft N is operated by the band-pulley G instead of the usual mode, and the clutch and clutch-gear are for the same reason dispensed with.

In order to make the connection more exact and certain between the gear F during the running-in motion, and the second driving-pulley A, instead of the scroll-clutch gear, catch-gear F¹ F³ is used, and a different mode is employed to keep these from coming into contact, and to regulate them after the belt has been thrown onto the pulley A, and while the backing-off is taking place.

To produce a steady starting motion when the carriage is about running in or out, instead of making gear C² fast to the shaft F², or the gear R to the shaft S, each is allowed to run loose on its shaft, and the connection of the gear C² to the running-in gear, and that of gear R to the running-out gear, is produced by bringing the face or disk of a friction-pulley, adjusted and made fast on the shaft, into contact with the face

or disk of said gear, and the motion is effected by the friction of the two, the necessary amount being practically ascertained and preserved by the adjustment.

The regulator, with its connections for governing the ball-lever, as well as the break which acts upon the first driving-pulley, are found to be no longer necessary, and are dispensed with.

The following is a description of the improvements claimed as my invention, reference being made to the drawings making part of this specification.

On the main shaft A² is added a gear, B, running loosely on the shaft with and attached to the second driving-pulley A.

Gear B¹, on shaft B⁴, meshes with B, and on the other end of this shaft is gear B², which plays into and operates gear B³, attached to the friction-pulley E¹, both running loosely on shaft X.

The shaft X also carries a band-pulley, E, and the ratchet-gear E⁶, both secured upon it, and a loose gear, E⁸, which, through a train of wheels, connects with the upper rack D⁴; also a pair of clutch-boxes, E⁹ and E¹⁰, and a bent bar, E⁵, around the collar of the clutch E⁹, (one end of which bar is secured by a pin to the pawl E⁷), all likewise loose. The shaft slides endwise in its bearings.

On the other end of the shaft is applied the end of a spring, E⁶, secured to the mule-frame, and of sufficient strength to press the band-pulley away from the friction-pulley and destroy the friction caused by its contact with the friction-pulley when no counter-force is in action.

The pawl E⁷ is pivoted to a pin on the side of the loose gear E⁸, and is arranged to hang over the ratchet-gear E⁶, and to turn on its bearing. The rear end of the pawl has a lip which by the pin is connected with the bent bar E⁵.

The clutches E² and E³ are confined within certain limits, viz: E² by a pin, K², let down from the shipper K, and by the arm E⁴.

E³ is attached through a rod, J¹, to the arm of the lever J.

Clutch E² has two projections, and E³ has corresponding openings of the shape and size to receive them.

The band-pulley G, instead of revolving on a stud, is set fast upon a revolving shaft, Y, upon which a fast pulley, G¹, is also set, having a hollow rim.

To the under surface of this rim are secured several pawls G⁸ G⁹ playing loosely, so that when the shaft and rim-pulley turn in one direction these pawls pass over the teeth of a ratchet-gear, G³, (which is placed loosely on the shaft and within the rim,) without catching them, but when turned in the other direction they enter and carry the ratchet and the pulley G⁴, to which it is attached, with the chains G⁵ and G⁶, fastened at one end to the periphery of the pulley G⁴, in the same direction.

One of these chains G⁵ acts simply to keep the other chain G⁶ taut, and for this purpose is carried over a loose pulley, and has a weight, G⁷, suspended from it. The other, G⁶, passes down over the periphery of a half-heart cam, H, and is fastened to it where the radius is diminished.

The cam H is set on the cop-rail or rock-shaft N, which is turned in its bearings by the chain G⁶ in one, and by the weight of the cop-rail in the other direction.

This shaft has, besides the arm connecting it with the cop-rail, the pulley L, (made without the pins or spurs,) around which the chain L¹, connecting the rack D⁴ and the weight L², passes, and also an arm to which the rod Z, connecting the curved arm Z¹ and the rod or bar U, are attached.

The other apparatus now used to regulate and operate the rack D⁴ on this shaft, and connected with it, is removed as useless, and leather or other straps of

sufficient strength may be substituted for the chains L¹, G⁶, and G⁵.

On the shaft F², catch-gear F¹ F³ are substituted for the scroll-clutch, so called.

F³ is attached to the gear F.

F¹ slides endwise on the shaft, and is operated by finger F⁴ from the shifting apparatus. It is made with projecting shoulders or collars, which, when the end of the lever J is in contact with the gear, prevent the two from closing.

The shaft also carries the loose gear C², which is connected by intermediate gear with the pulley A, and a friction pulley, F⁵, made fast on the shaft, fitting into the face or disk of C², and which is pressed against it by a suitable spring fixed on the frame, and acting on the end of the shaft which, for the purpose slides, endwise.

On the shaft S carrying the gear T, which through intermediate gear operates to run the carriage out, instead of a fast gear, I introduce a loose-gear, R, and a fast friction-pulley, S¹, arranged to run face to face, and adjustable so that, while the ordinary power is operating, the contact will produce the friction to drive the shaft S as effectually as if the gear R was fast upon the shaft; but, should any derangement of machinery produce an unusual strain, the friction will yield to the excess of power and preserve the machinery from breaking.

The lever J, one end of which is connected by the rod or bolt J¹ to the arm E⁴ of the clutch E⁹, has its fulcrum on the stud J², and is carried beneath the gearing and driving-pulleys, and, at the other end, is terminated by a broad face, flattened to be pressed against the recess formed by the shoulders of catch-gear F¹.

To this last arm of the lever J is connected, by a slotted rod confining a bolt secured to it, the arm J³ set upon shaft W.

This shaft rotates on bearings secured to the frame M, and carries also the arm V. On the end of the arm V is a pin, v'.

The rod U, above mentioned, is extended beyond the arm Q. Near its extremity a short adjustable bar, U', is set, and secured by a set-screw upon it. The arm or piece connecting the two forms a right-angle with the lower bar, and answers as a hook to hold the pin v', and may be rounded off at the corner of the upper bar.

The ends of the two bars pass through and slide in holes in a stand on the frame M that acts as a guide and support. To the arm Q is adjusted and secured a short arm, q, carrying a pin, q'.

This arrangement, while serving other purposes, enables me to dispense with the use of the pin in the curved arm Z, the hooked lever or bar operating on the pin, and the arm and pin on the arm Q, which operates the bar.

The mode of operating my improvements may be thus described:

When the driving-band is shifted from the first to the second driving-pulley A, the following operations take place:

Through the gear B and its connections, the friction-cone E¹ is put in motion in a direction the reverse of that of the band-pulley E.

At the same time the pin K², from the shipper K, moves the clutch E², whose projections press against the face or disk of clutch E⁹, and forces it and its collar against the ratchet E⁶, which, as already stated, is set fast on the shaft, and, by a further pressure, forces the shaft itself endwise, and thus brings the band-pulley E into contact with the friction-cone. This, moving in the reverse direction, acts upon the pulley E, at first stopping and then carrying it with the spindle-band, which is no longer driven by the band-pulley A¹.

on the main shaft, sufficiently far to reverse the motion of the spindles and loosen the yarn, so that the follower can come down without breaking it, preparatory to winding on.

The band, thus carried in the reverse direction, carries with it the band-pulley G and its shaft. This enables the beaks of the pawls G³, attached within the rim of the pulley G¹, to enter the teeth of the ratchet-gear G³, and this, put in motion, winds up on the pulley G⁴, the chain or strap G⁶, and turns the rock or cop-rail shaft N, to which the half-heart cam H is made fast, and operates the cop rail and the rods z and U.

The arm to which the rod U is attached, by the movement of the rock-shaft, pushes forward the rod, so that, as soon as the movement comes to an end, it has reached the point where the upper rod terminates and the pin v', resting upon it, is ready to descend to the lower one.

During this time the lever J has, by its attachment at one end to the clutch-gear E³, kept that gear in such a position that the projections of gear E² cannot enter the cavities in the former, and, by the intervention of the other end, has prevented the catch-gear F¹ and F³ from closing. The lever itself has been kept in position by the arm J³ acting through the rod or bolt and slot upon it, and the arm J³ is maintained in its position by the pin v' resting upon the upper bar of U, as before mentioned; and the pressure of the clutch E² upon E³ has also been such that the bar E⁵, bent on the collar of the latter, and one end of which is attached to the rear of the pawl E⁷, has prevented the beak from entering the teeth of the ratchet E⁶.

When, therefore, the pin v' is at the point above mentioned, the friction alone has been sufficient to back off the yarn, which is now in readiness to be wound onto the spindles.

The further pushing of the rod U leaves the pin v' without support, and, by the weight of the arm V, made sufficiently heavy for that purpose, it drops onto the lower bar.

This movement brings down the end of the arm J³, and with it the arm of the lever J to which it is connected, and which has presented an obstacle to the closing of the gear F¹ F³. These gears being thus freed, close immediately, and the connection is formed whereby the pulley A puts in motion the gear for running the carriage in.

At the same time the other arm of lever J rotates the clutch E³, so that its openings are brought opposite to the projections of E², which, under the pressure before mentioned, enter at once into them, and the pressure ceases. The shaft thus relieved is forced by the spring E⁹ endwise, removing the band-pulley E from contact with the friction-cone E¹, and the friction is destroyed. By the movement of the clutch E³ the rear of the pawl E⁷, connected to the bent bar E⁵, is tripped, and the beak is put into gear with the ratchet E⁶; this gearing of the pawl into the ratchet connecting the gear E⁹ with the band-pulley E, and through a train of wheels with the rack D⁴. Motion to the band-pulley is given by and through the rack D⁴,

the reverse of that given by the friction, and in conformity with the speed of the rack, fast or slow.

The spindle-band thus driven, acting upon the band-pulley G, releases the pawls G³ from the ratchet G³, and the pulley G⁴, no longer exerting any tension on the strap G⁶, leaves the cam H, with its shaft, to resume, by the weight of the cop rail, its proper position when the carriage is running out. But the rod U, held fast by the pin v' on the lower bar, where it answers the purpose of a hook, does not allow the cop rail yet to move until the carriage is in, when the pin q', by the rotation of the arm Q, is brought up under the arm V, and with it, raises the pin v' sufficiently high to release its hold, and, by the weight of the cop rail, the rod is drawn back. The pin v' then, released from the action of the pin q', rests upon the upper bar.

At this moment the shipper K transfers the belt to the first pulley, causing the clutch E², through the pin K², to leave the clutch E³, and, at the same time, by the movement of the arm J³, caused by the lifting of the arm V by the pin q', the clutch E³ is turned on the shaft, and the end of the lever is brought up under the catch-gear F³. This completes the winding-on motion, and the carriage is now ready to run out.

Having thus fully described the nature of my improvements and the mode of operating them,

What I claim therein as new, and desire to secure by Letters Patent, is—

1. The loose pulley E¹, connected with and driven from the main pulley A, in the manner substantially as and for the purpose of reversing the spindle in the mason, or other similarly-constructed self-acting mules.

2. The mechanism, substantially as described, for detaching the friction-pulley E¹ from the band-pulley E and connecting the latter with the loose gear E⁸, for the purpose described.

3. The band-pulley G, connected with and operating the rock-shaft and its connections, substantially as described.

4. The arms J, J³, and V, operated simultaneously by the pin q' at the completion of the inward run of the carriage, to hold the running-in catch-gear F¹ apart, and place the part of the clutch E³ in proper position to be operated upon, as described, at the completion of the outer run of the carriage to close the friction-pulleys and back off.

5. The combination with the arm of the rock-shaft N, of the arms U U¹, and arm V, provided with pin v', operating substantially as described, for the purpose specified.

6. The clutch F¹ F³ for running in the carriage, when constructed and operated substantially as described, from the backing-off mechanism.
